UNITED STATES PATENT OFFICE.

ADDISON WILEY, OF NEWARK, NEW JERSEY.

THERMOTIC REGULATOR FOR INCUBATORS.

SPECIFICATION forming part of Letters Patent No. 375,035, dated December 20, 1887.

Application filed February 25, 1887. Serial No. 228,896. (No model.)

To all whom it may concern:

Be it known that I, ADDISON WILEY, a citizen of the United States, residing at Newark, Essex county, New Jersey, have invented certain new and useful Improvements in Incubators, fully described and represented in the following specification and the accompanying drawings, forming a part of the same.

The object of this invention is to regulate automatically the temperature within an incubator; and the invention consists in means within the incubator for operating upon a ventilator and upon a heating-lamp.

In the drawings, Figure 1 is a vertical longitudinal section of the entire apparatus. Fig. 2 is a plan of the same. Fig. 3 is a side elevation of the thermostat upon a larger scale. Fig. 4 is a plan of the same, and Fig. 5 an end view of the same. Fig. 6 is a side elevation of the lamp-burner and its regulating-lever upon a larger scale, the chimney being removed.

The incubator consists in a casing, *a*, containing in its top and bottom water-tanks *b* and *c*, connected together at one end by a pipe, *d*, and at the other end by branches *e* *e'* to a boiler, *f*.

g is a lamp sustained below the boiler; *h*, its chimney; *i*, its wick-tube; *k*, a sleeve encircling the same, and *l* a lever pivoted upon the burner at *m* to actuate the sleeve to regulate the height of the flame.

j are shelves for the eggs; *n*, a ventilating-aperture in the top of the casing *a*, and *n'* an opening through the tank *b* underneath such aperture *n*.

p is a damper hinged by pivots *p'*, and furnished with an arm, *q*, by which it may be tipped to open and close the aperture *n*. A lever, *r*, pivoted upon the casing at *r'*, is connected at one end by rod *r''* to the lever *l*, and at the other end by a slot, *r'''*, to a pin, *r''''*, upon the damper *p*. The motion of the damper is thus imparted to the lever *l*, so that when the damper is opened to cool the incubator by ventilation the sleeve *k* is raised to partially cover the wick, and thus diminish the heat of the boiler and the tanks *b* and *c*.

The thermostat for actuating the damper and lever *r* is affixed within the incubator near the upper tank, where the air is hottest,

and consists in a bed-plate, *s*, having two expansion-bars, *s'* and *s''*, mounted thereon, and their united movement transmitted to a lever, *s''*. Each bar is formed of hard rubber—as, 55 for instance, a half-inch diameter and thirty to forty inches long—and has affixed in each end a projecting piece of brass to form its attachments. The bed is provided with loose guides *t*, which steady the bars above the middle of their length to prevent bending. Both the bars are pivoted at one end to a lever, *u*, movable upon a pivot, *u'*, fixed to the bed-plate *s*, and the bar *s'* is adjustably clamped, by lock-nuts *t'*, to a standard, *t*. 60

The movement of the bar *s'* is transmitted through the lever *u* to the bar *s''*, which is pivotally connected at its extreme end to the lever *s''*, so that the combined expansion of both bars is conveyed to such lever, which in turn operates upon the damper *p* through the medium of a lever, *v*, pivoted in the ventilating-aperture *n*. The lever *v* is connected, by a link, *v'*, to the arm *q* upon the damper, and to the lever *s''* by a link, *w*. The upper end 70 of the lever *s''* is provided with a swiveling nut, *w'*, and the end of the link *w* is furnished with a threaded stem, *w''*, by which the relation of the damper to the lever *s''* may be altered. 75

By means of the lock-nuts *t'* and the swiveling nut *w'*, which is fitted to turn without longitudinal movement in the end of the lever *s''*, the position of the damper at any given temperature within the incubator may be readily 80 varied to secure the right conditions for the desired temperature.

When in operation and the damper properly adjusted to the desired temperature, the flame of the lamp heats the water in the boiler 90 *f*, and the water then passes continuously in a circuit through the boiler and the tanks *b* and *c*. When the temperature exceeds the desired degree, the expansion of the thermostat-bars *s'* and *s''* operates to open the ventilating-damper 95 and to simultaneously diminish the flame of the lamp by elevating the sleeve *k*, and the generation of the heat is then reduced to the desired point, as in other constructions. Conversely, if the temperature falls below the de- 100 sired degree, the contraction of the thermostat-bars operates to close the damper and to

augment the flame beneath the boiler, so that the heat is increased in the required manner. I employ hard rubber for the thermostat-bars, because it has in other thermostats proved 5 to possess a large range of expansion and contraction.

Heretofore incubators have been provided with connections from the thermostat to the damper on the outside of the casing, while in 10 my construction such connections are so formed as to be adapted to operate within the casing, thus avoiding the necessity of perforating the casing to permit the passage of the moving parts, and avoiding also the derangement to 15 which the damper and its connections are subjected when such connections are located without the casing of the incubator.

Having thus set forth the nature and operation of my invention, what I claim herein is— 20 The combination, with an incubator having a water heating and circulating apparatus, of the casing *a*, the boiler *f*, the tanks *b* and *c*,

arranged in the top and bottom, respectively, of the incubator, the ventilating-aperture *n* in the 25 top of the casing, the opening *n'* in the tank beneath it, a lamp having a flame-regulating sleeve applied to its wick-tube, a thermostat arranged within the casing adjacent to the tank *b*, a connection from the thermostat to the damper within the casing through the 30 aperture *n*, as and for the purpose set forth, and a connection from the exterior of the damper to the flame-regulating sleeve to actuate the sleeve by the movement of the damper, the whole arranged and operated substantially 35 as shown and described.

In testimony whereof I have hereunto set my hand in the presence of two subscribing witnesses.

ADDISON WILEY.
